UNITED STATES PATENT OFFICE.

JOHN P. COOL, OF CAMPBELL, MICHIGAN.

FENCE.

SPECIFICATION forming part of Letters Patent No. 371,822, dated October 18, 1887.

Application filed May 27, 1887. Serial No. 239,575. (No model.)

To all whom it may concern:

Be it known that I, JOHN P. COOL, of Campbell, in the county of Ionia and State of Michigan, have invented certain new and useful Improvements in Fences, of which the following is a specification.

My invention relates to fences, and has for its object to simplify and cheapen their construction.

- 10 In the drawings, Figure 1 is a perspective view of a section of my improved fence; Fig. 2, a similar view looking from the opposite side; Fig. 3, a vertical sectional view on the line xx of Fig. 2, and Fig. 4 a top plan view. 15 A A indicate posts, B B' the braces, C C' C², &c., the rails, and D the binders, as shown in all the figures, these parts being firmly bound together by means of a wire, E, as hereinafter more fully described.
- 20 In constructing the fence the post A is first set up in position, and a block about six inches high (shown in dotted lines in Fig. 1) is placed near the foot of the post. Upon this block one end of the bottom rail, C, is placed, and 25 upon this bottom rail is placed the bottom rail of the adjoining section, as shown in Figs. 1, 2, and 3. The wire E is now passed about and secured to the post A below the rails C C and passed up on the front face of said rails, 30 over the top of rail C, and around behind post A. Two more rails, C', are now placed upon the rails C, and the wire is brought out from between rails C C', up across the front of rails C', and back around the post A, this 35 operation being repeated with each set or pair of rails C' C'. When the rails C' next to the top are reached, the wire is not only passed upward across their front faces, but is passed around behind post A, and down across their 40 front faces and between them and the rails C'. From this point the wire passes around behind post A, around braces B B', thence upward around the upper ends of the braces, post, and binding. In thus passing about the 45 parts last mentioned the wire is twisted or wound completely about the binder D, the latter during the binding operation being in a position substantially the same as the braces. When the winding is completed, however, the 50 lower end of the binder D is swung around to a position approximately parallel to the face, as shown in all the figures, and the lower end of the binder secured to the fence by means of a wire, as shown. In Fig. 1 there 55 is shown but one binder, but in Fig. 2 two

such binders are shown, connected at their lower ends to the fence and to each other. While in some cases it may be found desirable to employ two, I do not wish to limit myself to that number, because one of them may be omitted, if desired.

The top rail, C⁵, is held in the fork formed by the crossing of the braces B B', and the wire E, in passing about the upper ends of the braces, post, and binder, passes over the 65 top of rail C⁵, and thereby prevents it from getting out of place. After the fence is bound together the block is knocked from beneath the bottom rail and the post A driven into the ground a short distance. As the binder D 70 is swung around it tends to twist the wire E tighter upon the braces and post.

At various points on the post it will be found advisable to use staples *a* to hold the wire in proper position.

In constructing my fence the old rails now in use in ordinary farm-fences may be used without any dressing or finishing, and it will also be noticed that a fence can be constructed in accordance with my invention on level or 80 hilly ground with equal ease.

The number of rails may be varied as desired without departing from the spirit of my invention.

I am aware that fences similar in many respects to mine have been patented, and of course make no broad claim to this class of fences. My particular construction I believe possesses advantages over those heretofore patented, in that it is stronger and requires 90 no previous preparation of the rails and posts, thus enabling me to utilize the rails of ordinary farm-fences.

Having thus described my invention, what I claim is—

In a rail fence, the combination, with the upright posts A A, crossed braces B B', and binder D, all extending upward to approximately the same height, of the rider C⁵, a series of rails, C C', &c., and a single wire, E, secured at the lower end of the post and serving to bind the rails to the post, and also binding the upper ends of the post, braces, and binder to one another and to the rider, all substantially as shown.

In witness whereof I hereunto set my hand in the presence of two witnesses.

Witnesses: JOHN P. COOL.

O. MARKHAM,
RUBY A. MARKHAM.
